(57) **CLAIM**

The ornamental design for a CD player, as shown and described.

DESCRIPTION

FIG. 1 is a side elevational view of a CD player showing my new design.

FIG. 2 is a back elevational view of the CD player.

FIG. 3 is a front elevational view of the CD player.

FIG. 4 is a top plan view of the CD player.

FIG. 5 is a bottom plan of the CD player; and,

FIG. 6 is a top perspective view of the CD player with the lid open.

The broken line showing on FIGS. 1 and 6 is for illustrative purposes only and forms no part of the claimed design.
